MULTIPLE SOUND AND PICTURE RECORD-
ING AND PROJECTION SYSTEMAlexander McLean Nicolson, New York, N. Y.,
assignor to Communication Patents, Inc., New
York, N. Y., a corporation of DelawareApplication May 27, 1930, Serial No. 456,037
Renewed July 29, 1936

9 Claims. (Cl. 178—6)

This invention relates to the recording and projection of sound and pictures, and particularly to the recording and reproduction of sound from a plurality of associated sources together with concomitant pictures.

An object of this invention is to record a plurality of sources of sound upon a single record, and to reproduce said sound from the single record.

10 Another object of the invention is to record a plurality of sound sources with concomitant television scannings into a single record, and to reproduce the record for simultaneous projection.

A further object of the invention is to record 15 for later reproduction a scene in its colors and accompanying sounds, as for instance a stage presentation, the sound being particularized to definite positions to accompany the sound sources when reproduced.

20 A still further object is to transmit a plurality of signal sources on a single carrier frequency channel.

Heretofore, sound and pictures occurring in the same scene have been recorded simultaneously 25 and reproduced simultaneously. The reproduction has been made by the projection of the pictures on a screen and the reproduction of the sound behind or near the projection screen. It frequently occurred that a scene was projected 30 wherein the object originating the sound was shown at the extreme left portion of the picture screen, while the sound was reproduced to the right of the screen, providing a distorted and unreal reproduction of the original occurrence. No 35 attempt was made to localize or position the sound in accordance with the projection of the picture, nor to present any binaural effect thereto.

This invention contemplates providing apparatus for recording a scene in its natural colors 40 and recording concomitant sound, the sound being reproduced with the picture and in accordance with the actual place of occurrence in the original. Furthermore, the invention contemplates recording pictures and accompanying 45 sound upon a single recording medium such as film or disc record by having individual sound tracks for recording sound picked up by several spatially disposed microphones with respect to the sound sources. The pictures may be recorded in the usual manner by using moving picture film, while the sound tracks are interposed therebetween. The recording may also be accomplished by modulating each individual sound source at a different modulation frequency 50 and modulating the whole with another prefer-

ably higher frequency for recording all of said sound sources in a single record strip. In this manner television impulses may be combined with sound impulses, all of which are modulated with the recording or transmitting frequency. The 5 reproduction from the single film track is accomplished by the use of band pass filters for segregating each particular sound source. Simultaneous transmission of the various sound sources or television source through space or over wires 10 may be accomplished with this single carrier transmission frequency. Each modulating frequency, of course, may transmit the same source of sound in different phase relationships, in order to provide binaural, multiaural, or directional 15 effects. Certain of these features are being claimed in the divisional application Serial No. 701,698, filed December 9, 1933.

Details of the invention will be more fully understood by reference to the accompanying drawings, in which:

Figure 1 is a line diagram of either a recording or projection system;

Fig. 2 is a view of the film used in the system in Fig. 1;

Fig. 3 is a diagrammatic illustration of a system of recording sound and television impulses as individual sound records on a single film strip.

Fig. 4 is a diagrammatic view of a recording system for sound and television as a single track;

Fig. 5 shows the reproducing system for Fig. 4.

Referring particularly to Fig. 1, three cameras or projectors 5, 6 and 7 are shown associated with three individual sound recording or reproducing systems 9, 10 and 11.

The sound currents are derived from microphones or reproduced in loud speakers 13 associated with sound system 9; derived from microphones or reproduced in loud speakers 14 associated with sound system 10; and derived from microphones or reproduced in loud speakers 15 associated with the sound system 11.

In recording, the output from sound systems 9, 10 and 11 pass into the sound recorder 17 for impression on a film 18 which passes through cameras or projectors 5, 6 and 7 over the guide rollers 19.

A source of supply for the various units is shown at 20. The projectors 5, 6 and 7 are focused on a screen 22. The three projectors are used to project the scene in three colors, for instance in red, blue, and orange, the mixture of which upon the screen presents the usual scene in its proper color scheme. When the devices 5, 6 and 7 function as cameras, the screen is eliminated, and whatever scene is presented is re-

corded in the three colors in any well known manner such as individual color screens before the cameras. The microphones are so displaced around the screen that they are actuated by the sound occurring in their immediate vicinities and during reproduction loud speakers reproduce this sound in the same or substantially the same position. The two series of speakers 13 and 15 may present sound binaurally as disclosed in my Patent No. 1,852,624 of April 5, 1932.

By the use of multiple cameras and projectors, scenes may be recorded and projected with stereo effects, the two angles of recording and projection producing the depth dimension.

15 Referring to Fig. 2, the three picture tracks are shown as 25, 26 and 27 which may be the recording of the respective cameras 5, 6 and 7. The sound tracks 29, 30 and 31 may be the sound recordings from the respective sound systems 9, 10 and 11. 20 The film is shown with the usual sprocket teeth holes 24 used for driving the film.

Fig. 3 shows a film 35 with two sound recordings 36 and a television recording 37. The light variations are projected from light projecting apparatus 39 and 30 and the television light variations are projected from apparatus 41. The various projectors are shown disposed laterally across the film and may be offset for convenience of arrangement, the same displacement being maintained 30 at the reproducer. The television recording is shown as a single light developed track, since the picture is broken up into various units by the scanning process.

Referring to Fig. 4, various details of the recording system are illustrated. Four microphones 50, 51, 52 and 53, which may either detect separate and distinct sound sources or the same sound source at different phase displacements, are connected to respective modulator systems 55, 56, 57 40 and 58 which have associated with them respective oscillators 60, 61, 62 and 63. These oscillators provide different modulating frequencies separated from one another sufficiently to prevent any interaction or interference between the products of modulation. The outputs of the modulators are impressed upon a single modulator 65 through a switch 66. The modulator 65 is provided with a frequency considerably above the frequencies being generated by the individual 50 oscillators 60, 61, 62 and 63 from an oscillator 67. After the second modulation the products thereof are fed into a recording lamp 69 for projection onto a sensitized film 70. Such projection will form the sound track 71. The recording lamp, of course, may be replaced by an aerial system or a wire system for transmitting the single carrier modulations to reproduction apparatus. The sound track may be composed of either the carrier plus the side bands or only one side band, the carrier and the other side band being eliminated in a manner well known in the art.

In a branch input circuit of the modulator 65 is a second switch 73 which connects the modulator 65 to a modulator 74 which is supplied from an 65 oscillator 75. This oscillator generates a frequency which is different from any of the other oscillations and, preferably, between the frequencies of the sound modulating oscillators and the carrier oscillator 67 because of the respective frequencies being modulated. The input to the modulator 74 is a photoelectric cell 77 which receives reflected light from an object 78 being scanned by light projecting through a pinhole camera 79 from a moving arc on screen 80. Any 70 well known system of scanning such as a rotating

disc may be employed in this invention, but an electrodynamic arc in a magnetic field is preferable. Such a scanning system is described in my Patent No. 1,868,278 of June 14, 1932.

The frequencies generated by the photoelectric cell 77 are, after modulating by the modulator 74, impressed on the modulator 65 for recording on the film 70. By use of the switches 66 and 73 recordings of both pictures and their concomitant sound from microphones 50, 51, 52 and 53 may be recorded simultaneously, or recordings from either of said sources may be made.

Referring to Fig. 5, the receiving system or reproduction apparatus for the recorder or transmitter of Fig. 4 is shown. The film 70 with its sound track 71 is passed between a source of light 85, energized from a source 86 and a photoelectric cell 87. The generated frequencies are impressed on a demodulator 88, associated with an oscillator 89, which generates the same frequencies as oscillator 67. If the carrier is recorded with a side band, however, the oscillator is not required. The output of the demodulator is transmitted to two switches 90 and 91 which transfer the output to the sound reproducing apparatus or to the picture receiver, respectively. In the input of the sound record-system are filters 93, 94, 95 and 96 for segregating the frequency bands carrying the particular sound frequencies corresponding to the microphones 50, 51, 52 and 53. These filters should be of the band pass type, passing bands of a frequency width comparable to the voice range. After the individual sound modulations are segregated, they are impressed upon the modulators 100, 101, 102 and 103 having respective oscillators 104, 105, 106 and 107 which correspond in frequency to the oscillators 60, 61, 62 and 63 of the recording system. Again, if the oscillator frequencies have been transmitted through the systems, the oscillators are not required. The output of the oscillators is impressed upon audio frequency amplifiers 110, 111, 112 and 113, respectively, and, for reproduction on loud speakers 115, 116, 117 and 118. These loud speakers may be disposed in such positions about a projection screen that they reproduce sound at substantially the same point as the sound originated in the original scene. Also if certain pick-up devices detect the same source at different positions, the corresponding loud speakers may be positioned around the auditorium or outdoors to reproduce the source with a binaural effect.

When picture frequencies are being transmitted, they are selected by a filter 120 and detected by a demodulator 121 with its associated oscillator 122, the output of the photoelectric cell 77 being passed to television receiving equipment 125 which may be of the electrodynamic arc or the neon cell type. The picture being received may be associated with the loud speakers 60 or may be individually received.

With the above disclosed invention the transmission of several sound sources which have been detected at different positions, together with a television recording may all be effected on a single carrier wave, thus utilizing to the maximum extent the broadcasting channels. Furthermore, a film record either as multiple recordings or as a single recording, may comprise an entire scene in its natural colors, stereoscopic effects, and accompanying sound with directional and binaural effects.

While the invention has been described in one of its preferred embodiments, I desire it to be understood that modifications may be made and

that no limitations on the invention are intended other than those imposed by the scope of the appended claims.

What is claimed is:

- 5 1. In a sound and picture recording system, a plurality of pick-up devices for sound and a source of television frequencies, means for segregating the sound frequencies into individual frequency channels, means for separating the picture frequencies from the sound frequency channels, and means common to all of said channels for simultaneously recording said sound and picture frequencies, said means including a common recording light source.

10 2. In a system for the recording of sound and pictures, means for generating electrical currents corresponding to picture variations, means for generating electrical currents corresponding to sound variations, said sound variations accompanying said pictures, and common means for simultaneously combining said pictures and sound currents into a unitary record, said means including a common recording light source.

15 3. In a sound and picture recording system, means for generating electrical currents corresponding to picture variations, means for generating electrical currents corresponding to sound variations, said picture variations corresponding to said sound variations in accordance with the position of the source, and means for simultaneously combining said picture and sound currents into a unitary film record, said means including a common recording light source.

20 4. In a sound and picture recording system, means for translating a plurality of acoustic and television signals into a corresponding plurality of electrical signals, means for shifting said signals to mutually exclusive frequency bands, means for modulating a common frequency current with all of said shifted signals, and means for impressing said last modulations as a unitary record on a recording unit.

25 5. In a sound and picture recording system, means for translating a plurality of acoustic signals into a corresponding plurality of electrical signals, means for shifting said signals to mu-

30 6. In a sound and picture recording system, means for translating a plurality of acoustic signals into a corresponding plurality of electrical signals, means for translating the light and shade densities of an object into electrical signals, means for generating a carrier frequency, means for modulating said carrier frequency with said electrical signals, a recording medium, and means for recording said carrier in a continuous unitary record on said recording medium.

35 7. In a sound and picture recording system, means for generating electrical currents corresponding to picture variations and means for generating electrical currents corresponding to sound variations, a recording element, a recording medium, and means for simultaneously impressing the current corresponding to all of said variations on said element, whereby a continuous unitary record is made on said medium.

40 8. In a sound and picture recording system, means for generating a plurality of independent currents corresponding to picture variations, means generating electrical currents corresponding to sound variations, a recording medium, and means for simultaneously combining all of said currents corresponding to said picture and sound variations into a continuous unitary record on said medium.

45 9. In a sound and picture recording system, means for generating electric currents corresponding to picture variations in accordance with the colors of an object or image thereof, means for generating electric currents corresponding to sound variations in accordance with the location of the sound source in said object or image, and means for simultaneously recording all of said variations into a unitary record.

ALEXANDER MCLEAN NICOLSON.
